(57) **CLAIM**

The ornamental design for a dog food bag as shown and described.

DESCRIPTION

FIG. 1 is a front, right, and top perspective view of a dog food bag, showing my design.

FIG. 2 is a front elevation view thereof.

FIG. 3 is a rear elevation view thereof.

FIG. 4 is a left side elevation view thereof.

FIG. 5 is a right side elevation view thereof.

FIG. 6 is a top plan view thereof.

FIG. 7 is a bottom plan view thereof; and,

(Continued)

FIG. 8 is a front, right, and top perspective view of the dog food bag, in an open position.

1 Claim, 8 Drawing Sheets
